UNITED STATES PATENT OFFICE.

WILLIAM F. SCOTT, OF ALEXANDRIA, INDIANA.

DESIGN FOR A DISPLAY-RACK.

SPECIFICATION forming part of Design No. 27,603, dated August 31, 1897.

Application filed July 15, 1897. Serial No. 644,733. Term of patent 3½ years.

To all whom it may concern:

Be it known that I, WILLIAM F. SCOTT, a citizen of the United States, residing at Alexandria, in the county of Madison and State 5 of Indiana, have invented a new and original Design for a Display-Rack, of which the following is a specification.

This invention relates to a new and original 10 design for a display-rack; and it has for its object to provide a design of this character that shall be both useful and ornamental.

The leading feature of the design resides in 15 a pair of straight parallel base-strips and a series of regularly-spaced upright supports of an inverted-U form and spanning the space between the two strips, each of said supports having upright side portions provided intermediate their ends with short horizontal right-20 angular bends and a transverse horizontal top portion connecting the upper ends of said side portions and bent horizontally into a V-shaped figure disposed in a horizontal plane.

A minor feature of the design resides in 25 providing the base-strips at their upper edges with a single raised ridge extending from end to end thereof, and near one end with short upright headed projections.

In the drawings, Figure 1 is a perspective 30 view of a display-rack embodying the herein-described design. Fig. 2 is a side elevation of the rack. Fig. 3 is a top plan view thereof.

Referring to the accompanying drawings,

1 1 designate a pair of straight parallel base-strips, provided at their upper edges with a single raised ridge 2, extending longitudinally 35 from end to end thereof, and at their opposite ends with beveled faces 3. Directly adjacent to one end the base-strips 1 are provided with short upright headed projections 4, and said strips are connected together by a series of 40 regularly-spaced upright supports 5, the terminals of which supports enter the longitudinal ridges 2 of the strips. The upright supports 5 are of an inverted-U form, so as to span the space between the strips 1, and each 45 of said supports essentially comprises the opposite parallel upright side portions 6 and the transverse horizontal top portion 7, connecting the upper ends of said side portions 6. The side portions 6 of each support 5 are provided intermediate their ends with short horizontal right-angular bends 8, while the top portion 7 is bent into a V-shaped figure disposed in a horizontal plane. 50

What I claim is—

55 The design for a display-rack, herein shown and described.

In testimony that I claim the foregoing as my own I have hereto affixed my signature in the presence of two witnesses.

WILLIAM F. SCOTT.
